UNITED STATES PATENT OFFICE.

JOHN W. SMITH, OF PHILADELPHIA, PENNSYLVANIA.

MEANS FOR ROLLING THIN SECTIONS.

Application filed March 14, 1927. Serial No. 175,335.

This invention relates to the art of—and means for—rolling thin sections and, more particularly, to the production of integral hub and disk type of wheels for vehicles 5 such as automobiles and the like.

Attempts have been made to produce comparatively thin disk sections by forging, rolling or machining, but failed to comply with economical requirements necessary to 10 commercialize the integral hub and disk type of wheel or the integral hub and brake drum. In my co-pending application Serial Number 133,432; filed the 3rd day of September, 1926; I have set forth a two-stage 15 process of fabricating thin sections involving a high-speed rolling mill for the second stage. Under such process I am enabled to roll die forged blanks to thin sections by utilizing the heat retained in the blank— 20 after a "first stage" forging. Cycloidal rolling, by multiple passes, has been found highly advantageous in producing comparatively thin sections from relatively thick material when carried out at high speeds; 25 inasmuch as, such sections expand more readily when cycloidally rolled than when rolled with a straight line motion.

Cycloidal rolling and multiple drive eliminates the buckling or plaiting of the metal 30 when rolling near the outer edge and facilitates reducing a comparatively thick material to the required thin section in one pass, making use of the second pass as a finish, or eliminating it entirely on certain classes 35 of work.

Arcograph rolling is often an advantage in producing the final shape. My integral hub and brake drum is a typical example to 40 illustrate my multiple drive arcograph rolling and forms a part of my process for making integral hubs and brake drums and similar articles.

Maximum reduction in reducing metal by the rolling process is to be had when power 45 is applied to all of the rolling means in this particular case, one revolving forming die is employed, and two reducing rollers, each of the three means being supplied with power.

Having briefly outlined the mechanical organization involved I will now set forth the novel features more particularly. Primarily, it is well to here remark, that during the rolling period I aim to maintain 50 co-operative synchronized torque between the motors driving the rolling and forming

means. Such synchronized or balanced torque might be attained by mechanical means, but I prefer to control the momentum of the forming die so that it attains the proper 60 synchronized speed when the milling rollers are initially moved into rolling location, inasmuch as a surface speed change of four-to-one between the outer and inner periphery may be necessary in some cases. In other 65 words, I aim to maintain a co-operative speed and torque for the forming die with a balanced torque as between the motors driving the rolling means, by automatically synchronizing the surface speeds of the 70 forming die with the milling rollers.

The primary object of the instant invention, accordingly, is to roll thin sections with a combined radial—or cycloidal—and synchronized surface speed as between the forming 75 and rolling means at all the varying co-operative positions assumed incidental to the rolling operation.

Another object is to efficiently fabricate such sections with greater rapidity than is 80 at present possible by known means.

Other objects and advantages will be apparent from the following description of a typical means effective to carry out this invention; while the appended claims serve to 85 define those features alleged as novel and patentable.

In the drawings

Fig. I is a sectional view of the upper portion of a rolling mill adapted to my present 90 improvements.

Fig. II is an axial section through a pre-formed or forged blank ready for rolling in accordance with this invention.

Fig. III is a similar view illustrative of 95 the section after radial rolling in accordance with one phase of the present invention; and,

Fig. IV is a corresponding section of a typical product of the present invention subsequent to a final stamping and machining 100 operation.

Before entering upon a detailed explanation of the mechanism typified as suitable for carrying out my present improvements 105 in the art of rolling thin sections, I would here remark that this invention is mainly—though not essentially—concerned with the rolling of suitable blanks into comparatively thin sections by aid of automatically synchronized multiple-drive instrumentalities. 110 In view of the fact that the mill illustrated

in Fig. I generally conforms to that described in my co-pending application Serial Number 713,425, supra: the following description will be limited to a superficial explanation except in so far as the novel features of the instant case are concerned. The forming die 5 is rotatably held suspended in the main housing 6 of the mill with capacity for vertical adjustment by the means shown at 7, and it is appropriately secured to the lower circumferentially extended portion of a revolving die head 8 journaled in said housing. This die head 8 is sustained in place by a cap-piece 9 seating over an annular ledge of the housing 6, and a thrust bearing 10 thereunder, so as to ensure perfect freedom of rotation. As a means for driving the revolving die head 8 I—preferably—make use of a co-operate—torque variable—speed motor 11, designed to furnish the required torque or moment of force required by the revolving die 5.

This motor 11 is supported upon the top of the mill 6 by means of a suitable mounting 13 secured to the ring 12, while the shaft 14 of said motor is coupled direct to the revolving die head cap-piece 9 by a coupling 15.

A suitable blank 16—such as shown in Fig. II for example—is sustained in the mill resting against the extraction pin 17 and securely held in place by a stud 18 mounted on the turret-head 19, which has capacity for rotary—and vertically slidable—movement; all as described in the hereinbefore referred to co-pending application.

The rollers 20 functional to radially expand the blank 16 relative to the forming and rolling die 5 are provided with shafts 21 journaled in ball and roller bearings 22, 23—respectively—in turn appropriately secured in trunnion housings 24, 25 sustained by a trunnion support A mounted on the mill main columns 26. Each housing 24, 25 is fitted with a cap piece 27 serving to support the electric motors 28, 29, respectively; which are directly connected to the aforesaid shafts 21 through the medium of couplings 30.

Having briefly outlined the mechanical organization involved I will now set forth the novel features more particularly. Primarily, it is well to here remark, that during the rolling period I aim to maintain co-operative synchronized torque between the motor 11 and motors 28, 29. Such synchronized or balanced torque might be attained by mechanical means, but I prefer to control the momentum of the forming die 5 so that it attains the proper synchronized speed when the milling rollers 20, 20 are initially moved into rolling location adjacent the blank boss 31, inasmuch as a surface speed change of four-to-one between the outer periphery and said boss may be necessary in some cases.

In other words, I aim to maintain a co-operative torque for the die 5 with a co-operative balanced torque as between the motors 28, 29 by automatically synchronizing the surface speeds of the die 5 with that of the rollers 20.

In conjunction with the means just explained I employ a rheostat 34 for automatically regulating the strength of a shunt field 35 of the motor 11, with a co-ordinating connection 36, pivoted at 37 to one—25 for example—of the trunnion housings, and similarly connected at 38 to the switch arm 39 of said rheostat. Thus it will be readily appreciated that, as the milling rollers 20, 20 swing radially relative to the forming die 5, the resistance in the shunt field circuit 35 of the motor is automatically controlled.

The requirements for driving rollers 20, 20 are constant revolutions per minute and constant torque.

The requirements for driving the die 5 are entirely different. Near the center the revolutions per minute are high with a correspondingly light torque, and on the outer edge the revolutions per minute are low with a heavy torque. The above requirements are in accord with shunt wound motor specifications requiring a light torque with a weak field, and a heavy torque with a strong field.

Rolling at constant periphery speed as set forth is an important factor in my process. Applying the automatic rheostat to motor 11, the requirements are more easily met than if applied to motors 28 and 29. The three motor or multiple drive herein shown represents a drive of the simplest form. The die head 8 is driven by a variable speed shunt wound motor with an automatically operated rheostat 34. The milling rollers 20 are driven by motors 28 and 29 which are compound wound motors with a suitable premeditated speed factor between no load and full load.

In this particular case the series field circuits 32 of motors 28 and 29 are connected in parallel. Some motor manufacturers would prefer to connect the series fields in series for motors 28 and 29. The shunt field for motors 28 and 29 are herein shown in parallel but they may also be connected in series. Motor 11 may also be supplied with a series field winding connected in series with motors 28 and 29 as a means of augmenting co-operative performance.

The power lines for the motors 11 and 28, 29 are, respectively, designated by the numerals 40, 41, although it will be readily understood that all of said motors may be served from one such line; while such indications—in this case—are solely by way of illustrating diagrammatically one convenient arrangement.

Referring once again to Fig. I it will be

remarked that I have shown the face of the die 5 is of a curvature not struck from a common center but rather of gradual deviation outwardly therefrom, with the result 5 that the milling rollers 20, 20 roll the blank 16 cycloidally to tapering cross section. On the other hand my present invention is particularly well adapted for the rolling of thin sections having the dished contour depicted at 42 in Fig. III, that is to say with a definite radial curvature and of even sectional gage. Such profiled sections are particularly well adapted for subsequent die stamping to the sectional form—shown at 10 43 in Fig. IV—and useful as integral hub 15 and brake drum units for thin section spokeless wheels.

From the foregoing it is thought my present invention will be well understood, and 20 while I have outlined one typical embodiment thereof, it is to be understood that I hereby reserve the right to vary the means adaptable for ensuring the generic aspects of said invention so far as is compatible 25 with reasonable interpretation accorded the subjoined claims.

Having thus described my invention, I claim:

1. In a rolling mill embodying a rotary 30 forming die and co-operative rolling means movable radially of the forming die, the combination of means with automatic control to positively drive the forming die and the rolling means at synchronized surface 35 speed in different co-operative positions assumed incidental to the rolling operation.

2. In a rolling mill embodying a rotary 40 forming die and co-operative rolling means movable radially of the forming die, the combination of means to positively drive the rolling means at synchronous speed, separate means to drive the rotary forming die, and automatic means to control the drive means aforesaid for maintenance of 45 synchronized surface speeds between the rotary forming die and the rolling means in different co-operative positions incidental to the rolling operation.

3. In a rolling mill embodying a rotary 50 forming die and co-operative rolling means movable radially of the forming die, the combination of means to positively drive the rolling means at synchronous speed, separate means to drive the rotary forming die, and automatic means controlling co-ordination of the respective drive means for 55 maintenance of co-operative balanced torque between the several drive means.

4. In a rolling mill embodying a rotary 60 forming die and co-operative rolling means

movable radially of the forming die, the combination of means to positively drive the rolling means at synchronous speed, separate means to drive the rotary forming die, and a control functional to co-operatively 65 balance the torque between the respective drive means.

5. In a rolling mill embodying a rotary forming die and co-operative rolling means 70 movable radially of the forming die, the combination of an electric motor to positively drive the rolling means at synchronous speed, a separate electric motor to drive the rotary forming die, a rheostat in circuit with said latter motor, and means adapted to automatically vary the strength 75 of a shunt field—through said rheostat—synchronously controlled by the varying location of the rolling means.

6. In a rolling mill embodying a rotary 80 forming die and co-operative multiple-rolling means movable radially of the forming die, the combination of an electric motor with means to varyingly balance the speed 85 of each rolling unit, a separate electric motor to drive the rotary forming die, and a rheostat—operatively co-ordinated with one of the rolling units—functional to vary 90 the electro-motive force through a shunt field of the forming die motor, whereby the torque of the latter is co-operatively balanced relative to that of the rolling unit motors incidental to the peripheral speeds of said rolling units.

7. In a rolling mill embodying a rotary 95 forming die and co-operative multiple-rolling means movable radially of the forming die, the combination of an electric motor with a series and shunt fields adapted to each rolling unit, a separate similar motor 100 to drive the rotary forming die, and a rheostat co-ordinated with one of the rolling units functional to vary the strength of the shunt field of the rotary forming die motor 105 whereby the torque of the several motors is co-operatively balanced.

8. In a rolling mill embodying a rotary forming die and co-operative multiple-rolling means movable radially of the forming 110 die, the combination of an electric motor for each operative unit with a parallel circuit for series and shunt fields, means functional to co-operatively balance the torque between the respective motors, and the aforesaid series field and shunt field circuits 115 being connected in parallel.

In testimony whereof, I have hereunto signed my name at Philadelphia, Pennsylvania, this 10th day of March, 1927.

JOHN W. SMITH.
